DESIGN FOR A DISPENSING CARTON

Zygmunt Wolteger and Henry Lerer,
New York, N. Y.

Application January 21, 1942, Serial No. 105,345

Term of patent 14 years

To all whom it may concern:

Be it known that we, Zygmunt Wolteger and Henry Lerer, citizens of the Republic of Poland, residing at 15 Park Row, Room 810, New York city, in the county of New York and State of New York, have invented a new, original, and ornamental Design for a Dispensing Carton, of which the following is a specification, reference being had to the accompanying drawing, forming part thereof.

In the drawing, the figure is a perspective view of a dispensing carton showing our new design.

The side of the dispensing carton not shown in the drawing is substantially the same as that illustrated and the back of the said dispensing carton as well as the top of the lid thereof are substantially plain.

We claim:

The ornamental design for a dispensing carton, as shown and described.

ZYGMUNT WOLTEGER.
HENRY LERER.
